UNITED STATES PATENT OFFICE.

WILLIAM T. PHEANIS, OF WEST ELKTON, OHIO.

ENGINE-STARTER.

1,175,471.

Specification of Letters Patent. Patented Mar. 14, 1916.

Application filed August 14, 1915. Serial No. 45,522.

To all whom it may concern:

Be it known that I, WILLIAM T. PHEANIS, a citizen of the United States, residing at West Elkton, in the county of Preble and State of Ohio, have invented certain new and useful Improvements in Engine-Starters, of which the following is a specification.

My invention relates to new and useful improvements in starting mechanisms for internal combustion engines, the primary object of my invention being the provision of a mechanical starting device for the engines of self-propelled vehicles, particularly of pleasure vehicles of such character.

At present, the internal combustion engines of automobiles are commonly started by means of a hand crank having a detachable clutch connection with the forward end of the crank shaft of the engine. This method of starting engines is not only difficult and inconvenient but also dangerous and detrimental to the engine itself. The location of the starting crank oftentimes necessitates the driver standing in snow or mud while starting the engine and, furthermore, considerable muscular effort is required, particularly in starting high powered engines. If the crank shaft is not turned rapidly enough, the engine is apt to back fire and cause serious injury to the person cranking it, as well as possible injury to the engine. Furthermore, it is oftentimes impossible to prevent racing of the engine immediately after starting it as the control of the throttle and spark is, of course, located near the driver's seat and out of reach of the driver when he is at the front of the machine. This idle racing of the engine is not only wasteful of fuel, but also apt to be detrimental to the engine.

For these reasons, a still further object of my invention is to construct a starting mechanism of such a character that it may be conveniently and easily operated from the driver's seat, but one hand and foot being required to operate the entire starting mechanism and the driver, therefore, being able to immediately control the speed of his engine when it starts.

A still further object of my invention is to so construct the starting mechanism that it will be automatically thrown out of operation as soon as the engine starts and to so proportion its parts that considerable leverage is obtained, thereby permitting more rapid turning of the crank shaft and so de-

creasing the likelihood of back firing of the engine.

With these and other objects in view, my invention will be more fully described, illustrated in the accompanying drawings, and then specifically pointed out in the claims which are attached to and form a part of this application.

In the drawings, Figure 1 is a fragmentary top plan view of a motor vehicle, parts being broken away to show my starting mechanism applied; Fig. 2 is a side elevational view of my starting mechanism, portions of the vehicle being shown in dotted lines to more fully disclose the location of the various parts of the device; Fig. 3 is a fragmentary elevational view, partially in section, of the structure shown in Fig. 2, upon an enlarged scale; Fig. 4 is a top plan view of the starting mechanism, a portion of the driving clutch being shown in section; Fig. 5 is a perspective view of the driving clutch and its controlling pedal; Fig. 6 is an unassembled perspective view of a compound pawl member employed in my starting mechanism; Fig. 7 is a detail sectional view taken on the line 7—7 of Fig. 3.

Corresponding and like parts are referred to in the following description and indicated in all the views of the drawings by the same reference characters.

In order to clearly disclose the application and operation of my invention I have illustrated it as applied to a conventional form of automobile, indicated by the numeral 10 and having the usual internal combustion engine 11, the crank shaft 12 of which extends into the forward portion of the hood. Mounted upon the forward end of the crank shaft 12, is a pair of co-acting clutch collars 13 and 14 which, together, constitute the driving element by means of which power is imparted to the crank shaft. The abutting faces of these clutch collars are provided with the usual bevel faced clutch teeth 15 for interlocking engagement with each other and the collar 13 is formed intermediate its length with a peripheral groove or channel 16 to receive a roller 17 carried by the fork arms of a shipper lever 18 which is pivoted at its free end to a bracket 19 secured to the frame of the vehicle, the lever extending transversely of the vehicle. The clutch collar 13 is free for longitudinal movement along the crank shaft 12 of the engine, but is secured to such shaft to turn

therewith by a key 20 or other suitable means. The clutch collar 14, at its outer end, is provided with a bevel gear 21 which meshes with a bevel pinion 22 keyed or otherwise secured upon one end of a counter-shaft 23 which extends transversely of the vehicle and which is journaled in suitable bearings 24 carried by the frame of the vehicle. This shaft, at its opposite end, carries a pinion 25 which meshes with a spur gear 26 freely mounted upon a stub shaft 27 journaled in a bearing 28. It will, therefore, be seen that any rotation of the spur gear 26 will be transmitted through the pinion 25 and bevel gears 22 and 21 to the crank shaft 12 if the clutch collars 13 and 14 are in interlocking engagement with each other.

As a means for moving the clutch collars into and out of engagement with each other, I provide a link 29 which is pivotally connected at one end to the intermediate portion of the lever 18 and at its opposite end to one arm of a bell crank lever 30 which is pivotally supported by the frame of the vehicle. The shank 31 of a foot pedal 32 passes through the floor of the car at a point convenient to the driver's seat and is pivotally connected to the opposite arm of the bell crank lever 30, this shank being passed through a U-shaped supporting bracket 33 secured to the lower face of the floor of the car. The pedal is normally held in raised position by a helical spring 34 engaging the bracket 33 at one end and the lower face of the pedal at the other and, in raised position, the pedal holds the clutch collar 13 out of engagement with the clutch collar 14. A depression of the pedal against the tension of the spring 34 will, therefore, result in throwing the clutch collars into locking engagement with each other, although the collars will immediately move out of such engagement upon release of the pedal.

In order to provide means for manually turning the spur gear 26, such gear is formed with a recess 35 in its inner face and the peripheral wall about this recess is formed with ratchet teeth 36 concentrically disposed with respect to the shaft 27. Supported upon the shaft 27 and loosely mounted thereon, is a pawl carrying block 37. This block is disposed within the recess of the gear 26 and is formed at its opposite ends with grooves or recesses 38 forming seats for the cylindrical head portions 29 of swinging pawl carrying arms 40. As best shown in Figs. 3 and 6 of the drawings, these heads and the seats 38 are so proportioned that the heads are snugly journaled in the seats and the arms still free for considerable swinging movement, although they can be disengaged from the block 37 only by outward movement through the open ends of the seats. These seats are closed at

one end and when the device is assembled, the block is mounted upon the shaft 27 in such a manner that the body portion of the gear 26 in itself serves as a closure for the other ends of the seats, as clearly shown in Fig. 7. Each of the arms 40 is substantially sector-shaped including spaced parallel blade portions 41 which extend radially with respect to the shaft 27.

Secured to the vehicle frame, at a point below the floor of the car, is a guide loop 42 or bracket through which is reciprocally mounted a slide 43. Rods 44 and 45 are bent laterally at one end and passed through the forward end of this slide and threaded to receive nuts 46 and the opposite ends of these rods are similarly bent and passed through the end portions of the blades 41 of the pawl carrying arms 40 and secured by nuts 47 which seat in recesses formed in the outer faces of the inner blades, as shown in Fig. 7. Pivotaly mounted between the blades 41 of the pawl carrying arms 40, are the pawls 48 and 49, the rear end of the former pawl being adapted to engage the ratchet teeth 36 near the upper portion of the gear 26, while the forward end of the latter pawl is adapted to engage the ratchet teeth near the lower portion of the gear. These pawls are pivotally supported by the pawl carrying arms upon the terminals of the rods 44 and 45 which are passed through such arms, thereby doing away with the necessity of additional pivots. Furthermore, it should be noted that these pawls are of such a character as to be constantly held in engagement with the ratchet teeth through gravity. A movement of the carriage 43 in a forward direction will cause a forward swinging of the free ends of both pawl carrying arms 40, with the result that the lower pawl 49 will force the gear 26 in a counterclockwise direction, looking at the gear from the direction shown in Figs. 2 and 3 of the drawings, while the upper pawl 48 will ride idly over the teeth. Upon reversing the direction of movement of the carriage 43, the upper pawl will actively engage the teeth to continue the rotation of the gear in the same direction, while the lower pawl will ride idly over the teeth. It will, therefore, be seen that a reciprocation of the carriage 43 will result in imparting a continuous rotary movement, in one direction, to the gear 26.

A hand lever 50 extends through a slot in the floor of the car and at its lower end is pivoted to the frame, as shown at 51. This hand lever is provided intermediate its length with a longitudinal slot 52 which receives a pin 54 extending from the carriage 43. It will, therefore, be clear that oscillation of the hand lever 50 will result in reciprocation of the carriage 43.

In use, assuming that the various control

levers of the engine are properly set, the driver, while still in his seat, presses one foot upon the pedal 32 to bring the clutch collars into locking engagement with each other 5 and, with his foot still upon the pedal, oscillates the hand lever 50. This oscillation of the hand lever reciprocates the carriage 43 and, consequently, imparts a continuous rotary movement to the gear 26 and from this 10 gear through the countershaft 23 to the crank shaft 12 of the engine. As soon as the engine starts, this crank shaft will revolve at a higher rate of speed than it is possible for the operator to turn the counter- 15 shaft 23, with the result that the clutch collars are automatically thrown out of engagement with each other in spite of the pressure exerted by the operator upon the pedal 32. As soon as the engine starts and the clutch 20 collars are thus thrown out, the operator will remove his foot from the pedal and release the lever. Inasmuch as this starting is accomplished wholly from the driver's seat, and requires the employment of but one 25 hand and one foot of the operator, it will be clear that the spark and throttle levers may be readily manipulated as soon as the engine starts to prevent racing of the engine. The leverage obtained by the above described 30 mechanism is such that the crank shaft may be manually rotated at a higher rate of speed than the ordinary driver of an automobile is capable of rotating it with the customary hand crank now in use. As a result, there is 35 very little likelihood of back firing.

It will, of course, be understood that although I have illustrated and described my starting mechanism in all its details, I reserve the right to make any changes, within 40 the scope of the appended claims, at any time, without in the slightest degree departing from the spirit of my invention.

Having thus described the invention, what is claimed as new is:

45 1. In a starting mechanism for internal combustion engines, the combination with the crank shaft of an engine, of co-acting clutch collars mounted upon the shaft, one being freely mounted upon the shaft and the other to turn therewith but capable of movement longitudinally toward and away from the first, a shifter lever engaging the second

50 collar, a foot pedal operatively connected to the lever, means normally holding the foot pedal in position to hold the second collar 55 out of engagement with the first, a gear carried by the first collar, a countershaft, a gear carried by the countershaft and meshing with the gear of the collar, and means for rotating the countershaft.

60

2. A ratchet mechanism for engine starters including a shaft, a rotary power transmitting member mounted on the shaft and formed in one side with a recess, the peripheral wall of which is formed with ratchet teeth, a pawl supporting member loosely mounted on the shaft, oppositely extending pawl carrying arms swingingly supported by such member, reversely disposed pawls mounted upon the arms, and means for 70 swinging the arms toward each other, first in one direction and then in the other.

65

3. A ratchet mechanism for engine starters including a shaft, a rotary power transmitting member mounted on the shaft and 75 formed in one side with a recess, the peripheral wall of which is formed with ratchet teeth, a pawl supporting member loosely mounted on the shaft, oppositely extending pawl carrying arms swingingly supported 80 by such member, reversely disposed pawls mounted upon the arms, rods pivotally connected to the arms, a hand lever, and operative connection between the hand lever and free ends of the rods.

85

4. A ratchet mechanism for engine starters including a shaft, a rotary power transmitting member mounted on the shaft and formed in one side with a recess, the peripheral wall of which is formed with ratchet teeth, a pawl supporting member loosely mounted on the shaft, oppositely extending pawl carrying arms swingingly supported by such member, reversely disposed pawls mounted upon the arms, rods pivotally connected to the arms, a hand lever, and operative connection between the hand lever and free ends of the rods, said connection including a reciprocally mounted slide to which the rods are pivoted, and a pin carried by the slide and extending through a slot in the intermediate portion of the hand lever.

90

In testimony whereof I affix my signature.

WILLIAM T. PHEANIS. [L.S.]
